Filed Dec. 14, 1972, Ser. No. 315,131

Term of patent 14 years

Int. Cl. D26—05

U.S. Cl. D48—23 A

FIG. 1 is a front elevational view of a lighting fixture showing my new design, rear being substantially identical.

FIG. 2 is a side elevational view of the lighting fixture of FIG. 1, the opposite side elevational view being substantially identical;

FIG. 3 is a bottom view of the lighting fixture shown in FIGS. 1 and 2;

FIG. 4 is a top plan view of the lighting fixture;

FIG. 5 is an enlarged fragmentary cross sectional view taken on line 5—5 of FIG. 1;

FIG. 6 is a side elevational view of an alternate embodiment of my new design; and

FIG. 7 is a bottom plan view of the alternate embodiment shown in FIG. 6, the mesh being partially shown for convenience of illustration, it being understood that the mesh is continuous over the surface indicated.

The fluorescent tube is shown in broken lines in FIG. 4 for illustrative purposes only. It is to be understood that the second embodiment differs from the first only in the number of support members.

I claim:

The ornamental design for a lighting fixture, substantially as shown and described.
